14 Claims. (Cl. 242—43.5)

1
The invention has reference to the package-building mechanism of a textile spinning, doubling or twisting machine of the type wherein the element, the reciprocatory movement of which results in the formation of the packages of yarn, thread or the like on the spindles, derives its rectilinear movement from a lifter shaft to which the package-building mechanism imparts oscillatory motion for the chase traverse and which may be rotated continuously to raise or lower said element independently of the package-building mechanism for the purpose of doffing or donning the bobbins or the like. For the purpose of this invention it is immaterial whether the reciprocatory element be the member carrying the yarn packages, e. g. the spindle rail of a ring frame, or the member which delivers the yarn or thread to the packages, e. g. the ring rail of a ring frame.

The object of the invention is to provide in a machine of such type an improved form of package-building mechanism possessing, amongst certain advantages which will be evident from the following description, the adaptability for use in producing any desired form of package, e. g. "cop build," or "roving build" or a combination of both, with a minimum of adjustment or alteration of its component parts.

In a textile spinning, doubling or twisting machine of the aforesaid type according to the invention, the lifter shaft of the package-building mechanism is actuated through the medium of an epicyclic gear of which the bodily fixed wheel or sun-wheel which rotates about a fixed axis is oscillated to effect the chase traverse of the reciprocatory element, and of which the planet wheel carrier receives a secondary drive of a unidirectional step-by-step character whereby the datum point of the sun-wheel's oscillations is progressively adjusted, another feature of the mechanism consisting of means effective to vary the amplitude of the oscillations of the sun-wheel in accordance with the desired shape of the yarn-package.

The invention may also provide in association with the package-building mechanism means effective to interrupt the oscillatory motion of the lifter shaft and to substitute a continuous rotary motion thereof for the purpose of moving the reciprocatory element directly to either the upper or lower doffing positions (as hereinafter defined) or to any given position intermediate the same.

Another feature of the invention is an arrangement whereby, at the commencement of the spinning operation on a fresh yarn package and

2
before the formation of the package proper is begun, the oscillation of the sun-wheel is modified so that the spindle-rails (or ring rails) are reciprocated rapidly with a short movement to produce a weft cop bunch for use in known manner in connection with the weft-changing mechanism on an automatic loom.

The manner in which the invention may be carried into effect will be more readily understood 10 from the following description of the application of the invention to a double-sided ring spinning machine in which the build of the yarn packages is achieved by using stationary ring rails and vertically reciprocated spindle rails, and 15 in which automatic doffing and donning mechanisms according to United States Patent No. 2,582,696 and United States patent application No. 197,162 are provided. A pictorial representation 20 of the headstock end of such machine is contained in Fig. 1 of the accompanying diagrammatic drawings; Fig. 2 is a fragmentary elevation of the doffing shaft and the parts of the mechanism associated therewith; Fig. 3 of the drawings 25 illustrates the movement of the spindle rails during the cycle of operations of the machine when producing weft copy packages. Figs. 4 and 5 are perspective views drawn on a larger scale than Fig. 1, respectively, showing the parts of the headstock mechanism which are (a) within the end compartment outside the partition 1 and 30 (b) within the compartment enclosed between the partitions 1 and 2. Fig. 6 is a fragmentary detail illustrating the structural connection between the spindle rail 4 and the lifter shaft 5. 35 Fig. 7 is a diagram of the electric circuit for automatically operating the controls referred to in the following description.

Referring to Fig. 1, it will be seen that the headstock mechanism is contained within three compartments separated by partitions 1 and 2. The entire headstock is enclosed by a casing (not shown) fitting over said partitions, the endmost compartment being accessible through an end door; the third compartment, which encloses the change-speed gears for the spindle-and-roller driving mechanism, is separated from the machine itself by a partition 3. One of the spindle rails is indicated at 4; said rails 4 may be suspended by chains 4a passing over sprockets 4b on a pair of rotatably mounted lifter shafts 5 extending longitudinally throughout the machine, said two shafts being suitably geared together so that both spindle rails are raised and lowered in unison. One of said lifter shafts 5 is driven by

the building motion; this shaft is furnished with an extension 5a projecting through the partitions 3 and 2. The reference numeral 6 indicates the shaft employed to transmit driving motion to the spindles and the drafting rollers, said shaft 6 being driven through the change-speed gear-train 7, 8, 9, 10, 11, 12 by the electric motor 13.

The formation of the yarn packages requires that the lifter shaft extension 5a shall be oscillated during the winding of the yarn upon the spindle to produce the required chase traverse, whilst the doffing and donning operations require that the shaft 5a shall be rotated through a sufficient arc of revolution to effect a comparatively rapid movement of the spindle rails from the final spinning position to the upper doffing position, or between the upper and lower doffing positions, or from the upper doffing position to the starting position. (By "upper doffing position" is meant the position of the spindle rails in which the spindles project upwardly through the rings to their maximum extent wherein the yarn packages are most accessible for manual doffing or appropriately located for cooperating with automatic doffing apparatus such as that which forms the subject of United States Patent No. 2,582,696.) The upper doffing position coincides with the donning position, i. e. in which the empty spindles receive the fresh bobbins or the like in accordance with the invention described in United States patent application No. 197,162. By "lower doffing position" is meant the position of the spindle rails in which the spindles are entirely withdrawn from the rings so that the yarn packages detached from the spindles in the manner employed in said automatic doffing apparatus may be removed laterally preparatory to the ensuing donning stage. By "starting position," is meant the position occupied by the spindle rails when spinning is resumed upon a fresh set of bobbins or the like. By "final spinning position" is meant the position occupied by the spindle rails when the yarn package formation has been completed. The oscillatory and rotary motions referred to are imparted through two separate mechanisms, the mechanism for effecting the oscillatory motion being associated with automatic means whereby the amplitude of successive oscillations is appropriately modified to suit the changes required by the building of various types of yarn package.

The mechanism for the oscillatory motion of the lifter shaft extension 5a comprises a constantly rotating heart-shaped cam 14 which is fixed on a shaft 15 driven through the worm-wheel 16 and worm 17 by a cross-shaft 18. The shaft 18 is driven through a gear train 19, 20, 21 and 22, by a motor 23, the wheels 19 and 20 being easily accessible for replacement by wheels producing a different gear-ratio if desired. Cooperating with the peripheral face of the cam 14 is a bowl or cam-follower 24 which is revolvably mounted on a lever 25 (hereinafter termed the "builder motion lever" pivoted at 26. The lever 25 is connected with the lifter shaft extension 5a by means of a transmission chain 27 of which one end is wound about a pulley 28 on a shaft 29 geared to the shaft 5a through the medium of the interposed epicyclic gear-unit hereinafter referred to, whilst the other end of said chain 27 is attached to a movable anchorage on the builder motion lever 25. Such anchorage is constituted by a roller 30 carried in the end of a link 31 at the end of the chain 27 and constrained

to bear against the arcuate face 32 on the underside of said lever 25.

The arrangement is such that the rotation of the heart-shaped cam 14 between the positions at which the cam-follower 24 is respectively in contact with the cam recess 14b and the cam nose 14a depresses the builder motion lever 25 and imparts through the chain 27 a part revolution to the lifter shaft 5 whereby the spindle rails 4 are raised from the bottom of their chase to the top thereof. The return in the opposite direction is either effected by the spindle rails sinking under their own weight, or by the use of a two-way driving connection between the lifter shafts 5 and the spindle rails 4, as described in United States patent application Serial No. 130,684, now Patent No. 2,625,049.

The angle through which the lifter shaft 5a is oscillated is modified for the purpose hereinbefore referred to by varying the amplitude of the pull exerted by the builder motion lever 25 on the aforesaid traverse chain 27; this result is achieved by moving towards or away from the fulcrum 28 of said lever 25 the aforesaid movable anchorage 30 of the traverse chain thereon, thus varying the effective length of the arm of the builder motion lever 25. The adjustment of said anchorage point is brought about through the medium of a second chain 33 (called the "build control chain") which is attached at one end to the end of the link 31, said build control chain 33 passing over a cam-shaped pulley 34 (called the "build control cam") which is mounted on a shaft 35 and arranged to be intermittently rotated through the worm-wheel 36, the worm 37 and the vertical shaft 38 (called the "doffing shaft"), the skew gears 39 and 40, and the shaft 41, by a ratchet wheel 42 fixed on the shaft 41. The skew gear 39 is part of a sleeve 43 loose on the doffing shaft 38 and which carries a single clutch-member 44 adapted to be engaged by a double clutch-member 45 which is splined on the shaft 38. The other end of the build control chain 33 is attached to another pulley 46 (called the "lift control pulley") for the purpose hereinafter described. The pawl 47, which cooperates with said ratchet wheel 42 is carried by a lever 48 oscillated through a link 49 by a crank 50 which is driven continuously by the heart-cam shaft 15, and the arrangement is such that variations in the position of the build control cam 34 in relation to the build control chain 33, effected through the aforesaid pawl and ratchet mechanism 47, 42, alter the effective length of the build control chain 33 and thereby shift the movable anchorage 30 of the traverse chain 27 respectively away from or towards the pivot 26 of the builder motion lever 25. The doffing shaft 38 is conveniently made in two sections coupled together as shown, the torque connection between them being provided by a shear-pin 38a designed to fracture if subjected to an excessive load.

The length of the build control chain 33 may also be regulated for the purpose of effecting initial setting adjustments by rotating the lift control pulley 46, preferably by manually operated worm gearing enclosed in the gear-box 51 and arranged to be actuated by a person in possession of a key which will fit the square end of the shaft 52. This mechanism provides additional means for altering the position of the movable anchorage 30 on the builder motion lever 25 so as to vary the amplitude of the oscillatory motion of the spindle rails 4.

The build control chain 33 is maintained taut by a weight 53 suspended by a chain 54 over a pulley 55 which is fixed on a shaft 56 carrying a pulley 57 connected by a chain 58 (called the "tensor chain") to the said movable anchorage 30 in such fashion as to tend to draw it in the direction opposite to the pull exerted thereon by the build control chain 33.

It is important that the build control chain 33 should be led, in its connection to the anchorage 30 on the builder motion lever 25, about a pulley 59 or like guide which is arranged in a position such that the point at which the chain 33 leaves said pulley 59 coincides as nearly as possible with the axis of the pivot 26, thus ensuring that the oscillation of the builder motion lever 25 does not affect the tension of the build control chain 33.

It is also important that when the heart-cam nose 14a is against the cam-follower 24 the locus of the movable anchorage 30 on the builder motion lever 25 (i. e. the face 32) should be an arc truly radial to the point at which the traverse chain 27 makes contact with the first guide pulley 60 over which said chain 27 is passed, ensuring that the adjustment of the movable anchorage 30 affects neither the tension of the traverse chain 27 nor the top position of the spindle rail 4 at any traverse.

The aforesaid epicyclic gear-unit, which is interposed between the shaft 29 and the lifter shaft 5a, comprises a sun-wheel 61 fixed on the shaft 29, a planet-wheel 62 meshing with said sun-wheel 61, a pinion 63 fast with the planet-wheel 62 and a spur wheel 64 which is fixed on the shaft 5a, meshing with the pinion 63. The planet wheel 62 is supported on a carrier 65 which is loose on the shaft 5a. The carrier 65 bears on its periphery a gear segment 66 which is geared to a pinion 67 on the shaft 35 through a gear-train 68, 69.

The top position of the spindle rail at each traverse, or the point at which each successive traverse chase commences, is determined by the aforesaid pawl and ratchet mechanism 41, 42 acting to transmit through the members 40, 39, 38, 37, 36, 35, 67, 68, 69 and 66 an intermittent rotary motion to the planet wheel carrier 65 of the epicyclic gear unit, and thence to the lifter shaft 5, whereby the point at which successive reciprocations of the spindle rails 4 commence is caused steadily to fall. As the traverse oscillations of the lifter shaft 5a proceed, the build control cam 34 operates to vary the length of successive traverses as required and the gradual adjustment requisite to produce the desired formation of the yarn packages on the spindles is achieved. The desired shape of the yarn packages will be governed by the shape of the cam 34, and the arrangement is such that any appropriately shaped build control cam may be substituted according to requirements.

Aligned with the doffing shaft 38 is a short shaft 70 on which is fixed a single clutch-member 71 adapted to be engaged by the double clutch-member 45 when the latter is shifted downwardly out of engagement with the single clutch-member 44 which is associated with the ratchet-driven skew-gear 39. Said clutch-member 71 bears a cam 72 which on rotation of the shaft 70 impinges against an abutment 73 carried by one arm 74 of a bell-crank lever 74, 75, the other arm 75 of which is connected to the double-clutch member 45, the arrangement being such that the lever 74, 75 is automatically tripped 76

to disengage the clutch 45 (and therefore the shaft 38) from the clutch 44 on the skew gear sleeve 43 and to engage it with the member 71. Said shaft 70 is geared through a worm-wheel 76 and worm 77 with a shaft 78 which is coupled to the shaft 79 of an electric motor 80 (called the "doffing motor"). A handle 81 is provided on the arm 75 of the clutch-shifting lever 74, 75 for the manual operation thereof. A cam 82 on said lever 74, 75 cooperates with a spring-pressed plunger 83 in such fashion as always to ensure the positive engagement of the clutch-member 45 with either the clutch 44 or the clutch 71.

The oscillatory motion of the lifter shaft 5a, due to the operation of the heart-shaped traverse cam 14, and the modified motion imposed on said shaft 5a by the build control cam 34, is interrupted when the formation of the yarn packages is completed or for any other reason it is desired to effect a rapid movement of the spindle rails 4 between the upper and lower doffing positions, or in any given section of such range of movement.

The machine incorporates a number of mechanical trip-switches A, B, C, D, E, F and G, a master control switch H, a manual bunching motion switch BM and a time-relay switch T, whereby the circuits of the several electric motors driving the various component mechanisms are controlled in the manner hereinafter described. The shaft 35 carries two cycle plates 84 and 85, respectively provided with adjustable detents 86 and 87; the detent 86 cooperates with a trip-switch A which controls the circuit of the doffing motor 80, whilst the detent 87 is arranged to actuate a trip-switch B in the circuit of the heart-cam motor 23. The heart-cam shaft 15 carries two cycle plates 88 and 89, respectively provided with adjustable detents 90 and 91; the detents 90 and 91 respectively cooperate with the trip-switches C and D which control the circuit of the heart-cam motor 23 in such fashion that when alternately closed they stop and restart said motor 23 in the reverse direction. The switch D also serves to stop the heart-cam motor 23 before the spindle rails are raised for doffing and ensures that the heart-cam 14 remains with its nose 14a in contact with the cam-follower 24. The trip-switch E is associated with the circuits of the spindle-and-roller driving motor 13 and the heart-cam motor 23, and is adapted to cooperate with the clutch handle 81 in such manner as to ensure that said motors 13 and 23 cannot be re-started when the pawl-and-ratchet mechanism is disengaged. A trip-switch F, included in the circuit of the doffing motor 80, is actuated by a peg 92 on the spindle rail 4 in such manner as to stop the spindle-and-roller motor 13 and the doffing motor 80 when the spindle rails 4 reach the upper doffing position. A trip-switch G, controlling the doffing motor circuit when the spindle rails are being returned by the motor 80 to the lower doffing position, is actuated by a peg 93 on the spindle rail when the rails reach the lowermost position. The master control switch H is provided for selecting and closing the several motor circuits appropriate to the respective operations of the machine. Said switch H may be set by hand, as in the ensuing description of the machine cycle, or by automatic means if desired. The bunching operation hereinafter referred to is controlled by a manual switch BM (hereinafter called the "bunching-motion switch") and a time-relay

switch, both of which are included in the control circuit diagram illustrated in Fig. 7.

The sequence of operations of the machine is as follows:

The cycle commences with the spindle rails in the starting position indicated in Fig. 3 by the reference P. Fresh bobbins have been placed on the spindles and the severed ends of yarn applied to the bobbins, either manually or by the automatic means described in the copending patent application No. 31,973/1949, in readiness for spinning. The switch H is set to the position I, and the clutch handle 81 is raised to couple the pawl and ratchet mechanism 42, 47 to the shaft 38. This action completes the starting relay, comprising the contactors SR(1) and SR(2), closing the contact SR(1) and opening SR(2). In addition the main contactor M and the contactor HF which control the forward direction of rotation of the heart cam 14 are energized thereby starting the spindle and roller motor 13 and the heart cam motor 23. The auxiliary contacts M(1) and M(2) are also closed to complete the "holding-in" circuit. The spinning operation now commences, winding yarn upon the empty bobbins. (The previous doffing and donning operations having been performed with the nose 14a of the cam 14 in contact with the cam-follower 24 ensures that the spindle rails will commence their downward movement from the position P and correctly initiate the build of the yarn packages simultaneously with the commencement of the spinning operation.)

When producing "roving build" packages, spinning is commenced with the movable anchorage 30 at a point remote from the fulcrum 26, such that the first traverse of the yarn extends over the full length of the required package. As the formation of the package proceeds, said anchorage 30 is steadily drawn towards the fulcrum point 26 so as steadily to reduce the length of the traverse. This can be accomplished either by using a build control cam 34 of circular form and attaching the end of the chain 33 thereto, so that the chain is wound around said cam 34, or merely by using a cam of a shape which will bring about the required steady retraction of the anchorage 30.

To provide "eft" cops with bunches for use in conjunction with the weft-changing mechanism of an automatic weaving loom, the spindle rails are reciprocated rapidly with a short movement. This operation may be performed at any desired point within the first chase. For this purpose, the bunching motion switch BM has been turned to the "on" position before the machine is started. During the rotation of the heart camshaft 15, the detent 91 on the cycle plate 89 opens the limit switch D. The contactor HF is thus de-energized and the contactor HR, which controls the reverse direction of rotation of the heart cam is energized. The direction of rotation of the heart cam is thus reversed until the detent 90 on the cycle plate 88 opens the limit switch C (which is shown in Fig. 7 by switches C1 and C2 which operate together) which de-energizes HR and energizes HF π . In this manner the heart cam motor 23 is repeatedly stopped, reversed and re-started, after a short movement of the spindle rails in alternate directions, producing upon each bobbin a bunch of yarn, due to the repeated winding of turns of yarn upon the same part of the bobbin.

The duration of the bunching operation is determined by the time controlled relay T which,

when the bunch has attained the desired thickness, operates to open the contact T(1) and close the contacts T(2) and T(3), thus cutting out the limit switch D and allowing the heart cam to run forward through the HF circuit, and permitting the formation of the yarn packages to proceed normally. When bunches are not required, the bunching motion switch is turned to the "off" position before the spinning operation is commenced.

The successive vertical movements of the spindle rails throughout the formation of the yarn packages are indicated by the short vertical lines at the left-hand side of Fig. 3, the length 15 of each such line corresponding to the length of the chase traverse. When the yarn package formation is complete, the spindle rails arrive at the position Q (Fig. 3). The setting upon the cycle plate 85 of the detent 87 is such that the plate 85 has been slowly brought by the pawl and ratchet mechanism 42, 47 to the position in which the detent 87 opens the limit switch B simultaneously with the arrival of the spindle rails at position Q. At or about the same time, as the camshaft revolves, the limit switch C is opened by the detent 90 on the cycle plate 88 which rotates with the heart camshaft 15. The operation of switch C de-energizes the starting relay SR, which opens the auxiliary contact SR(1), stops the heart cam motor through HF and closes the auxiliary contact SR(2), stops the heart cam motor through HF and closes the auxiliary contact SR(2). This completes the circuit for the operation of "doffing up" and the doffing motor 80 is started. At the same time, the auxiliary contact DD(1) has been automatically opened to ensure that the "doff down" circuit is inoperative. During the formation of the yarn packages, the repeated opening of the switch C at each revolution of the shaft 15 has been ineffective, owing to the fact that the switch B has been closed. The setting of the detent 90 on the cycle plate 88 is such as to stop the motor 23 with the cam nose 14a in contact with the cam follower 24 for the reason already referred to.

The doffing motor 80 being started, the shaft 70 rotates and through the inter-engagement of the member 72 and 73, the clutch 45 is thrown to uncouple the pawl and ratchet mechanism and couple the shaft 70 to the doffing shaft 38. The clutch lever 81 is simultaneously lowered; this actuates the switch E (which is shown in Fig. 7 by switches E1, E2 and E3 which operate together) and serves to ensure that when the doffing cycle has been completed, the motors 13 and 23 cannot be re-started until the lever 81 is again raised and the pawl and ratchet mechanism re-engaged.

The shaft 38 is now continuously driven to raise the spindle rails rapidly from position Q to the upper doffing position R, the spindle and roller motor 13 remaining in operation.

When the spindle rails reach position R, the impingement of the peg 92 on the limit switch F opens said switch F and breaks the circuit to the operating coils of the doff-up contactor DU, the main contactor M, the contactor HF (heart cam forward), the starting relay SR and the contactor HR (heart cam reverse). As DU is de-energized, the auxiliary contact DU(1) is closed. At this stage, the motors 13 and 80 are stopped and the entire machine is at rest.

The switch H is next set to the position II. The "doff down" contactor DD is thus energized and the doffing motor 80 starts in the reverse

direction to lower the spindle rails rapidly to the lower doffing position S, where the peg 93 actuates the limit switch G (which is shown in Fig. 7 by the switches G1 and G2 which operate together, i. e. as G1 is opened and G2 is closed and vice versa). In addition, DD is de-energized and the control relay AR is operated, opening the auxiliary contact AR(2) and closing the auxiliary contacts AR(1) and AR(3). These actions stop the doffing motor 80 and closure of the switch AR(1) ensures that AR is energized when the limit switch G is actuated as the spindle rails rise in the next operation. During this "doff down" stage, the spindles have been withdrawn from the intercepted bobbins so that the latter are free to be doffed. When a new set of empty bobbins has been placed ready for donning, the switch H is set to the position III. The "doff-up" contactor DU is energized and the doffing motor 80 is re-started so that the spindle rails are raised to insert the spindles into the bobbins; this movement is terminated when the limit switch F is again opened by the peg 92 to stop the doffing motor 80 at the position T (Fig. 3).

The switch H is next adjusted to the "reset" position IV, starting the motor 80 and lowering the spindle rails to the position P, when the actuation of the limit switch A (shown in Fig. 7 by switches A1 and A2 which operate together) by the detent 86 on the cycle plate 84 de-energizes DD and stops the motor 80. At this time, the closure of the limit switch illuminates the signal light SL to show that the cycle of operation is complete.

The switch H is moved again to position I and the clutch handle 81 is raised by hand to de-clutch the shaft 70 and recouple the pawl and ratchet mechanism to the shaft 38, the machine then being ready to commence spinning upon the new bobbins. The action of raising the clutch handle operates the limit switches E1, E2 and E3. The switch E3 opens to de-energize AR and cut out the signal lamp, whilst the switch E2 opens the contactor DD to ensure that the "doff down" switch position is inoperative. The switch E1 closes, to complete the start circuit, is complete.

The auxiliary contacts HR(1) and HF(1) are safety contacts to ensure that the reverse circuit of the heart cam motor cannot be in operation when the motor is operating through the forward circuit and vice versa. Similarly the auxiliary contacts S(1) and S(2) ensure that the main motors are isolated when the doffing operation is in progress. The over-current relays 1/OCR, 2/OCR and 3/OCR respectively control the spindles and roller motor, the heart motor and the doffing motor. These relays are normally closed but in the event of an overload on the circuit would open to isolate the motors. The normally closed push button marked SB is a stop button which may be operated by hand to stop the whole machine.

What I claim as my invention and desire to secure by Letters Patent is:

1. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily

fixed wheel and the other a planet wheel carrier, means for oscillating the bodily fixed wheel to effect the chase traverse of the reciprocatory element, means for imparting unidirectional travel to the planet wheel carrier, whereby the datum point of the bodily fixed wheel's oscillations is progressively adjusted, and means to vary the amplitude of the oscillations of the bodily fixed wheel in accordance with the desired shape of the yarn package.

2. A machine as set forth in claim 1, in which means is provided for causing the lifter shaft oscillating mechanism to operate with a short, rapidly repeated stroke.

3. A machine as set forth in claim 1, in which means is provided for automatically controlling the operation of the epicyclic differential gear in accordance with a predetermined cycle.

4. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel

5. A machine as set forth in claim 1, in which means is provided for imparting to the bodily fixed wheel a degree of oscillatory motion proportional to the chase traverse length, means for varying the amplitude of such oscillatory motion, and means to impart to the planet wheel carrier of the epicyclic gear a progressive intermittent rotary motion to vary the datum point

35 of the oscillation of the bodily fixed wheel.

5. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel

40 and the other a planet wheel carrier, means for oscillating the bodily fixed wheel to effect the chase traverse of the reciprocatory element, means for imparting unidirectional travel to the planet wheel carrier, whereby the datum point of the bodily fixed wheel's oscillations is progressively adjusted, means to vary the amplitude of the oscillations of the bodily fixed wheel in accordance with the desired shape of the yarn package, means for interrupting the oscillatory motion of the lifter shaft, and means for im-

45 parting to said shaft a continuous rotary motion by which the reciprocatory element may be moved directly either to the upper doffing position or to the lower doffing position, or to any selected intermediate.

6. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel

50 and the other a planet wheel carrier, means for oscillating the bodily fixed wheel to effect the chase traverse of the reciprocatory element, means for imparting unidirectional travel to the planet wheel carrier, whereby the datum point of the bodily fixed wheel's oscillations is progres-

55 sively adjusted, means to vary the amplitude of the oscillations of the bodily fixed wheel in accordance with the desired shape of the yarn package, means for interrupting the oscillatory motion of the lifter shaft, and means for im-

60 parting to said shaft a continuous rotary motion by which the reciprocatory element may be moved directly either to the upper doffing position or to the lower doffing position, or to any selected intermediate.

6. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel

sively adjusted, means to vary the amplitude of the oscillations of the bodily fixed wheel in accordance with the desired shape of the yarn package, an alternative continuous rotary drive for the planet wheel carrier, means for temporarily disconnecting the intermittent driving means of the planet wheel carrier and substituting said alternative drive therefor, and means for regulating the alternative drive as to direction and timing either manually or automatically.

7. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel and the other a planet wheel carrier, means for oscillating the bodily fixed wheel to effect the chase traverse of the reciprocatory element, means for imparting unidirectional travel to the planet wheel carrier, whereby the datum point of the bodily fixed wheel's oscillations is progressively adjusted, means to vary the amplitude of the oscillations of the bodily fixed wheel in accordance with the desired shape of the yarn package, the driving means for the bodily fixed wheel comprising an oscillatory lever, and means to vary the effective length of the lever for adjusting the length of the chase traverse.

8. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel and the other a planet wheel carrier, means for oscillating the bodily fixed wheel to effect the chase traverse of the reciprocatory element, means for imparting unidirectional travel to the planet wheel carrier, whereby the datum point of the bodily fixed wheel's oscillations is progressively adjusted, means to vary the amplitude of the oscillations of the bodily fixed wheel in accordance with the desired shape of the yarn package, the driving means for the bodily fixed wheel comprising a shaft on which the bodily fixed wheel is made fast, a pulley fast on said shaft, a flexible member drivingly engaged with the pulley, an oscillatory lever, an anchorage on the lever to which one end of said flexible member is made fast, the lever having an arcuate face, and the anchorage including a roller which rides on said face, a second flexible member connected to the anchorage, and a cam engaged with said second flexible member to change the effective length thereof, thereby to shift the position of the anchorage along the lever.

9. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel and the other a planet wheel carrier, means for oscillating the bodily fixed wheel to effect the chase traverse of the reciprocatory element, means for imparting unidirectional travel to the planet wheel carrier, whereby the datum point of the bodily fixed wheel's oscillations is progressively

adjusted, means to vary the amplitude of the oscillations of the bodily fixed wheel in accordance with the desired shape of the yarn package, the driving means for the bodily fixed wheel comprising an oscillatory lever, means to vary the effective length of the lever for adjusting the length of the chase traverse, pawl and ratchet mechanism, means continuously driving the pawl and ratchet mechanism during the operation of said lever, and gearing transmitting the intermittent motion of the ratchet mechanism to the planet wheel carrier of the epicyclic gear.

10. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel and the other a planet wheel carrier, means for oscillating the bodily fixed wheel to effect the chase traverse of the reciprocatory element, means for imparting unidirectional travel to the planet wheel carrier, whereby the datum point of the bodily fixed wheel's oscillations is progressively adjusted, means to vary the amplitude of the oscillations of the bodily fixed wheel in accordance with the desired shape of the yarn package, the driving means for the bodily fixed wheel comprising a shaft on which the bodily fixed wheel is made fast, a pulley fast on said shaft, a flexible member drivingly engaged with the pulley, an oscillatory lever, an anchorage on the lever to which one end of said flexible member is made fast, the lever having an arcuate face, and the anchorage including a roller which rides on said face, a second flexible member connected to the anchorage, and a cam engaged with said second flexible member to change the effective length thereof, thereby to shift the position of the anchorage along the lever.

11. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel and the other a planet wheel carrier, means for oscillating the bodily fixed wheel to effect the chase traverse of the reciprocatory element, means for imparting unidirectional travel to the planet wheel carrier, whereby the datum point of the bodily fixed wheel's oscillations is progressively adjusted, means to vary the amplitude of the oscillations of the bodily fixed wheel in accordance with the desired shape of the yarn package, the driving means for the bodily fixed wheel comprising a shaft on which the bodily fixed wheel is made fast, a pulley fast on said shaft, a flexible member drivingly engaged with the pulley, an oscillatory lever, an anchorage on the lever to which one end of said flexible member is made fast, the lever having an arcuate face, and the anchorage including a roller which rides on said face, a second flexible member connected to the anchorage, and a cam engaged with said second flexible member to change the effective length thereof, thereby to shift the position of the anchorage along the lever, and setting means

for adjusting the initial length of the second flexible connection.

12. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel and the other a planet wheel carrier, means for oscillating the bodily fixed wheel to effect the chase traverse of the reciprocatory element, means for imparting unidirectional travel to the planet wheel carrier, whereby the datum point of the bodily fixed wheel's oscillations is progressively adjusted, means to vary the amplitude of the oscillations of the bodily fixed wheel in accordance with the desired shape of the yarn package, the driving means for the bodily fixed wheel comprising an oscillatory lever, a cam follower carried by the lever, a continuously driven cam shaft, a heart-shaped cam on said shaft engaged with the follower for operating the lever, and means connecting the lever to oscillate the bodily fixed wheel, the planet gear carrier operating means comprising pawl and ratchet mechanism, and crank and link mechanism operated by the cam shaft in synchronism with the heart-shaped cam and connected to the pawl and ratchet mechanism to actuate the latter.

13. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel and the other a planet wheel carrier, means for oscillating the bodily fixed wheel to effect the chase traverse of the reciprocatory element, means for imparting unidirectional travel to the planet wheel carrier, whereby the datum point of the bodily fixed wheel's oscillations is progressively adjusted, means to vary the amplitude of the oscillations of the bodily fixed wheel in accordance with the desired shape of the yarn package, the means for normally imparting unidirectional drive to the planet wheel carrier comprising pawl and ratchet mechanism, and a first

rotary output member driven thereby, an alternative continuous rotary drive for the planet wheel carrier having a second rotary output member, a common transmission shaft for said two drives, a two-way clutch normally connecting the first rotary output member to the common transmission shaft, and means responsive to the starting of the alternative continuous rotary drive automatically to disconnect the first rotary output member from the common transmission shaft and to connect the second rotary output member to said common transmission shaft.

14. A textile spinning, doubling or twisting machine comprising, in combination, spindle and ring rails, one of which is a reciprocatory element movable up and down relative to the other, lifting mechanism for the reciprocatory element comprising a lifter shaft, an epicyclic differential gear connected to drive the lifter shaft, and having two driving members whose inputs are combined by it, the one being a bodily fixed wheel and the other a planet wheel carrier, means for oscillating the bodily fixed wheel to effect the chase traverse of the reciprocatory element, means for imparting unidirectional travel to the planet wheel carrier, whereby the datum point of the bodily fixed wheel's oscillations is progressively adjusted, means to vary the amplitude of the oscillations of the bodily fixed wheel in accordance with the desired shape of the yarn package, an alternative continuous drive mechanism for the lifter shaft, separate electrical drives for the mechanisms respectively oscillating and continuously rotating the lifter shaft, and a master control switch, together with a set of automatic tripping switches, governing the selective operation of said drives.

JAMES JACKSON HAYTHORNTHWAITE.
